(57) **CLAIM**

We claim the ornamental design for a cap, as shown.

DESCRIPTION

FIG. 1 is a front left perspective view of a cap embodying our new design.

FIG. 2 is a front elevational view of the cap of FIG. 1.

FIG. 3 is a rear elevational view of the cap of FIG. 1.

FIG. 4 is a left side elevational view of the cap of FIG. 1.

FIG. 5 is a right side elevational view of the cap of FIG. 1.

FIG. 6 is a top plan view of the cap of FIG. 1; and,

FIG. 7 is a bottom plan view of the cap of FIG. 1.

In the drawings, the broken lines on the cap represent stitching forming part of the claimed design.
